Primary Examiner — Robin V Webster(74) *Attorney, Agent, or Firm* — Paul M. Denk(57) **CLAIM**

The ornamental design for the arcuate disc for butterfly valve, as shown and described.

DESCRIPTION

FIG. 1 is an isometric view of the arcuate disc for butterfly valve of this invention;
FIG. 2 is a top plan view;
FIG. 3 is a bottom view;
FIG. 4 is a right side view;
FIG. 5 is a left side view;
FIG. 6 is a left side view of the disc turned 19°;
FIG. 7 is a right side view of the disc turned 19°; and,
FIG. 8 is a sectional view taken along the line 8-8 of FIG. 2.
